KNOCKDOWN DISPLAY RACK

Application filed July 30, 1932. Serial No. 626,997.

My invention relates to knock-down display racks, and one which is particularly adapted for displaying boxed candy, stationery, seeds, and other articles of merchandise which are put up in packages. The primary object of the invention is to provide a display rack of this character which is made up of fibre board blanks or blanks of any other suitable flexible material, which can be shipped in flat form; the parts being arranged to be removably connected, one with another, without the use of separate attaching means, so that they can be quickly assembled to form a display rack for rectangular boxes or packages, or for round or heart-shaped boxes or packages.

Further, to provide a rack comprising an upright to which is secured one or more rack members which are removably attached thereto at their upper ends and incline downwardly therefrom, their lower ends resting on suitable base or on a store counter, as the case may be; the said rack members being either channel shaped or V-shaped in end view, and each being divided into a plurality of receiving pockets, by removable partitions, whereby merchandise, such as boxes of candy or other packages placed therein will be displayed to advantage, as each box or package will extend above the preceding box or package in step relation, thereby presenting an artistic and attractive appearance, this arrangement permitting the boxes or packages to be conveniently removed and replaced.

Further, to provide a display rack of this character in which the parts are provided with cooperating interlocking slits whereby the rack members are removably secured to the upright, and the partitions are removably secured to the rack members; the parts being disconnected and spread out flat when shipped.

45 These and other objects which will hereinafter appear are accomplished in the manner illustrated in the accompanying drawings, in which:

Fig. 1 is a perspective view of a display rack arranged for either round or heart-

shaped boxes or packages, and showing three sets of box receiving pockets arranged in tiers and connected to a single upright.

Fig. 2 is a front view of a portion of the rack shown in Fig. 1, one set of pockets being supplied with heart-shaped boxes, the partitions of the adjoining set being removed.

Fig. 3 is a side view of the box-filled rack shown in Fig. 2.

Fig. 4 is a plan view of the blank which forms the bottom of a rack.

Fig. 5 is a face view of one of the partitions.

Fig. 6 is a perspective view of a display rack arranged for rectangular boxes or packages.

Fig. 7 is a front view of a rack of the style shown in Fig. 6, but showing a single set of pockets which are supplied with rectangular boxes or packages.

Fig. 8 is a side view of Fig. 7.

Fig. 9 is a plan view of the blank which forms the bottom and ends of the rack for rectangular boxes or packages.

Fig. 10 is a face view of one of the partitions for said rack.

Fig. 11 is a sectional view on the line 11-11 of Fig. 1.

Referring to Figures 1 to 5 of the drawings, the letter A refers to the upright or back board of the rack which is made up of a middle section 1 and end sections 2, the end sections being hinged to the middle section by a fabric strip 3, which is adhered to the sections, thus permitting the end sections to be folded over the middle section for convenience in packing or shipping. The sections are preferably ornamented to present an attractive appearance, and at a suitable distance from their lower edges they are each provided near their side edges with narrow slots 4, the upper halves of which are vertically disposed, and their lower halves are downwardly and inwardly inclined, as clearly shown in Figures 1 and 2. To each one of the sections is secured the upper end of a rack bottom which is V-shaped in cross section, the rack bottom 5 of the end sections being of less width and

depth than the middle rack bottom 6. Each rack bottom is in the form of a blank which is scored centrally of its width, as shown by the dotted line 7, Fig. 4, to facilitate the bending of the blank into V-shape, and the upper end of the bottom is formed with a hook 8 on each corner, the hooks being made as follows: The blank is folded along the scored line 7 and at a distance 10 from the top end, a portion of the blank is severed on a line 9 which extends from the folded edge to a point 10 near the adjacent corner, and then parallel with the adjacent edge for a short distance, then 15 out through the edge on a line parallel with the line 9. The hooks are formed by slitting the blank from the point 10 to the point 11, as shown in Fig. 4. The opposite end of the folded blank is cut off on a line 20 12 of such an angle, that when the upper end of the V-shaped bottom is secured to the back board, its lower end edges will rest squarely upon the base or counter, the angle at which the rack bottom inclines with 25 respect to the upright back defining the angles at which the upper end of the blank is cut off, so that the said end will rest squarely against the upright. The bottoms are secured to the upright by passing the 30 hooks 8 through the vertical portions of the slots 4, and then slipping the necks of the hooks into the inclined portions of the slots. The side edges of the rack bottom are provided with a number of slits 13, corresponding 35 to the required number of pockets, and these slits are on an angle parallel with the upper end of the folded blank, so that when the rack bottom is secured to the upright, the slits 13 will be vertically disposed as 40 shown in Fig. 3. In each pair of oppositely positioned slits 13 is placed a partition 14, in the form of a strip having short legs 15 at its ends, the lower edge of the strip between the legs being V-shaped. When the partitions 45 are placed in the slits 13, the legs extend down below the bottoms of the slits, and the inner edges of the legs prevent the bottom members from spreading and the space between each two partitions forms a 50 pocket for the reception of boxes or packages, as shown by Fig. 3, and while I have shown six pockets in the drawings, it will be understood that a greater or less number of pockets may be employed, and the inclination 55 of the rack bottom may also be at any desired angle with respect to the back board. In Fig. 1, I have shown three rack members, the middle member being wider and deeper 60 than the end members to accommodate the larger sized boxes or packages, and it will be understood that the V-shaped rack bottom is especially designed for either round or heart-shaped boxes, and while I have shown 65 three groups of racks, I may also arrange

them in single or double groups, as may be desired.

In Figures 6 to 10, I have shown a display rack designed for rectangular boxes, or packages, and in this arrangement I employ an upright back board B comprising a central section 16 and end section 17 which are hinged to the central section in the same manner as described in connection with Fig. 1, or, I may employ either a single section 75 as shown in Fig. 7, or two sections as may be desired.

The sections are provided at a suitable distance from their lower edges, with vertical slots 18 to receive the hooked ends 19 of the rack bottoms 20. The rack bottoms 20 are in the form of blanks which are scored in lines near and parallel with their side edges, as shown by the dotted lines 21 and the parts 80 between the scored lines and the side edges are bent up at right angles to form end strips 22. The hooked ends 19, extend a short distance beyond the upper ends of the end strips 22 and the hooks are formed by slits 23, which extend outward from the 85 score lines 21 to within a short distance of the side edges of the end strips and at such an angle that when the hooks are passed through the slots 18, and the rack bottom is inclined at the desired angle to the back board, the slits 23 will be vertically disposed, the neck of the hooks will rest on the lower edges of the slots 18, and the end of the rack bottom and of the end strips will rest 90 squarely against the back board as clearly 100 shown in Fig. 8. The edges of the end strips are provided with spaced slits 24 which are set at the same angle as the hook slits 23, and are adapted to receive the partition strips 25, which are provided with 105 slits 26, which are cut into their lower edges and near their ends and interlock with oppositely disposed slits 24, in the end strips to provide a series of pockets, as clearly 110 shown in the drawings.

The slits 13 in the V-shaped rack bottom, and the slits 24 in the channel shaped rack bottom may be increased in number and placed closer together so as to provide a series of narrow pockets, and by omitting partitions, pockets of greater width can be provided and in this way, pockets of different widths may be arranged in the same rack to provide for boxes or packages of varying thickness, thus giving variety in the display 115 of goods.

The character of display rack herein described is cheaply produced, light and of artistic appearance, and can be shipped in a flat or knock-down condition, as it requires 120 no separate fastening means, can be easily and quickly assembled by the purchaser.

Having described my invention, what I claim as new and desire to secure by Letters Patent, is:

1. A knock-down display rack made of fibre board and comprising an upright back made up of hinged sections having oppositely disposed slots adjacent their side edges and above their horizontal centers, rack members having hooks upon opposite corners of one end for an interlocking engagement with said slots, said rack members extending at a downward inclination from said back, the lower edge of said back and the lower ends of said rack member resting upon a support; slits in the side edges of said rack members which are vertically disposed when the rack members are in inclined positions, and transverse partition strips for the rack members having an interlocking engagement with oppositely disposed slits in the said rack members to form a series of pockets which are arranged in tiers.

2. A knock-down display rack comprising an upright back having oppositely disposed slots adjacent its side edges and above its horizontal center, a rack member V-shaped in cross section and having hooks on the opposite corners of one end for interlocking engagement with said slots, said rack member

extending at a downward inclination from said back, a plurality of spaced slits being formed in the side edges of the rack member which are vertically disposed when the said rack member is in an inclined position and partition strips which rest in oppositely disposed slits in the bottom member and engage the outer side portions thereof to form a series of pockets which are arranged in tiers.

3. A knock-down display rack comprising an upright, a member V-shaped in cross section having on the opposite corners of one end hooks for interlocking engagement with slots which are formed in said upright, said member extending at a downward inclination from said upright and having slots in its side edges, and vertically disposed transverse partitions which have an interlocking engagement with oppositely disposed slits in said member and form a series of pockets which are arranged in tiers, the parts of said rack when disconnected, being adapted to be spread out flat for convenience in shipping.
